UNITED STATES PATENT OFFICE.

ERIC LEOPOLD HUGO COSBY, OF FILLMORE, CALIFORNIA.

CABLE-SYSTEM-WELL-DRILLING TOOL.

1,253,791.

Specification of Letters Patent. Patented Jan. 15, 1918.

Application filed May 3, 1916. Serial No. 95,268.

To all whom it may concern:

Be it known that I, ERIC L. H. COSBY, a subject of the King of Great Britain, residing at Fillmore, county of Ventura, and State of California, have invented new and useful Improvements in Cable-System-Well-Drilling Tools, of which the following is a specification.

This invention relates to well drilling tools, and more particularly to well drilling tools for use in "standard" drilling operations, that is, in drilling operations wherein a bit or string of tools is reciprocated, as by means of a cable or the like. The invention has for its object to provide tools of the general nature stated which will not be liable to part due to crystallization which frequently occurs in tools as ordinarily constructed, due to the hammering, jarring and other vibration-imparting strains and stresses to which well drilling tools are usually subjected; well drilling tools and parts thereof, when parted, due to crystallization, or other causes, frequently cause great annoyance to drillers as the lower portions of the tools or string of tools will remain in the well hole and it is no easy matter in many cases to remove the same by fishing methods, and such parting more frequently occurs at the joints of the tools than elsewhere, frequently the threaded portions breaking away from the other portions with which they were originally integrally formed, such breakage usually leaving the threaded portion of the tool which broke away from its shank with the portions of the string and the cable above such joint while the tool *per se* falls to the bottom of the well hole or remains at the bottom in case of breakage while in its lowermost working position.

In accordance with the invention, an improved tool or tool joint, or tool portion is provided which is composed of dissimilar materials or dissimilar grades of material such as different steels, the main portion of the tool or joint and its thread or threaded pin being formed of a suitable quality of steel and a core extending therethrough, and preferably from end to end thereof, being formed of a different or higher quality of steel, or built up of several different grades of steel which prevents parting of the tool as simultaneous crystallization of the component parts of the tool is practically impossible; furthermore, the higher quality steel

core will strengthen the tool and a tool constructed of several different steels has great inherent strength due to the mutual strengthening and supporting of the different steel members of the tool. Ordinarily, the metal of which the screw pin or threaded end of the tool is formed is more likely to crystallize than the metal or metals forming the reinforcing core. A particularly advantageous construction is to provide a bore through the tool or tool joint, such bore being countersunk at its ends so that the core may be headed or riveted over at both ends and overlap the surrounding material of the basis metal of the tool. In certain applications of the invention to tools, it is desirable to have only the top section of the tool organized in accordance with the invention in order to avoid extending the higher grade steel reinforcements throughout the length of the tool. Tools so organized may be built up of a reinforced section carrying the thread, which section may be welded to remaining portions of the tool. In a modified form the tool or threaded end portion thereof may be built up of several concentric or otherwise disposed layers of steel or metals of grades different from the basic body metal, which different grades of metal would form the threaded portion and such metals may if desired be arranged in overlapping relation to provide for great strength.

With the above and other objects in view, the invention consists in the novel and useful provision, formation, combination, association and relative arrangement of parts, members and features, all as hereinafter described, shown in the drawing, and finally pointed out in claims.

In the drawing:

Fig. 1 is an end view of the threaded portion of an oil well drilling tool, which portion is adapted to be welded to other or cutting or drilling portions of the tool;

Fig. 2 is a side elevation of the tool portion shown in Fig. 1;

Fig. 3 is a view similar to Fig. 1 of a modified form of tool portion or joint;

Fig. 4 is a side elevation of the tool portion shown in Fig. 3; and

Fig. 5 is a side elevation of a still further modified form of the invention, a drilling bit being illustrated in this figure.

The parts in the various figures are designated by reference characters.

Referring with particularity to the draw-

ing, in Figs. 1 and 2 thereof A designates the body portion of a tool joint, which body portion is provided with a longitudinal bore at *a* and countersunk at its ends as at 5 *a'* and *a''*, 6, 7, 8 and 9 designating respectively steel or other metal reinforcing members of metal dissimilar in grade or other qualities to the metal of the body portion A, as for instance the members 6, 7, 8 and 9 10 may be made of higher grade steel or of steel of great tensile strength and each of such members may if desired be formed of a different grade of steel. The members 6, 7, 15 8 and 9 are preferably segmental in form and are headed over at their ends as at 10 to fill the countersinks *a'* and *a''* in the body portion A, it being understood that the members fill the bore *a*. The member A is provided with a threaded end portion as 20 at 11, the threads being cut into the body portion A.

In the form of the invention shown in Figs. 3 and 4, a body portion B is provided and the same is bored from end to end as 25 at *b*, the body portion B comprising a tubular tool portion 12 of basic steel or other metal, concentric inserts 13 and 14 of dissimilar grades of steel or the like being provided in the bore *b*, the outer insert 13 being 30 provided with a bore 13^a into which the insert 14 is fitted. The threaded end *b'* of the tool portion is formed preferably as a taper joint and the same may comprise threads, 35 portions of which are formed on each or on more than one of the members of the tool portion.

In the form of the invention shown in Fig. 5, C designates a drilling bit bored from end to end as at *c* and provided in 40 such bore with a core *c'* which may be formed of segments of varying grades of steel or of a bar of steel of a different grade from that of which the main body C of the bit is formed. It will be understood that in 45 the form of the invention now being described the reinforcing or central core of the tool extends from end to end of the tool and the same may be headed over at the end of the threaded portion *c''* of the tool 50 and at the lower end thereof as at *c''*, this construction differing in the main, from the construction described in connection with the other figures, in that such other embodiment

ments of the invention, only a portion of the tool, namely, the threaded end portion is 55 formed in accordance with the invention.

The advantages and method of use of the invention will be readily understood from the foregoing description, taken in connection with the accompanying drawing and 60 the following statement:

The core of steel of a grade different from the basic metal of the tool in any of the forms of the invention will prevent parting of the tool at the base of the thread, as 65 crystallization of the basic metal and crystallization of the core could not occur simultaneously; thus should the basic metal part at the base of the thread, the tool will be held together, due to the still uncrystallized longitudinal core; furthermore in tools so constructed of dissimilar steels crystallization is not as apt to occur, due to the mutual reinforcement and strengthening of the tool by its component parts. 70

Having thus disclosed my invention, I claim and desire to secure by Letters Patent:

1. In a tool, a body having a threaded end and a core of dissimilar material whereby said body and said threaded end may be held together in case of crystallization. 80
2. In a tool, a body portion of suitable material having a threaded end, and a reinforcing core extending through said threaded end and into said body; said reinforcing core being of higher grade material than said body. 85
3. In a tool of the character disclosed, a body portion, a threaded portion, and a member of material different from said body portion uniting said threaded portion with said body portion. 90
4. In a tool joint, a body portion and a threaded pin comprising in part higher grade material than the material of said body portion whereby separation of said threaded pin and said body portion, due to crystallization is prevented. 95
5. In a tool joint, a body portion, and a threaded pin comprising in part material of a grade different from the basic material of said body portion and whereby separation of said pin and said body portion due to crystallization is prevented. 100

ERIC LEOPOLD HUGO COSBY.
